Primary Examiner — Catherine S Posthauer(74) *Attorney, Agent, or Firm* — The Webb Law Firm**CLAIM**

The ornamental design for a container closure, as shown and described.

DESCRIPTION

FIG. 1 is a perspective view of a container closure showing our new design in accordance with a first embodiment of the invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a perspective view of a container closure showing our new design in accordance with a second embodiment of the invention;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top view thereof; and,

FIG. 14 is a bottom view thereof.

The portions of the container closure shown in broken lines form no part of the claimed design.
